UNITED STATES PATENT OFFICE.

RALPH C. SEYMOUR, OF NEW YORK, N. Y., ASSIGNOR TO C. B. COTTRELL & SONS COMPANY,
OF NEW YORK, N. Y., A CORPORATION OF NEW JERSEY.

CUTTING AND FEEDING MECHANISM FOR PRINTING-PRESSES.

No. 872,464.

Specification of Letters Patent.

Patented Dec. 3, 1907.

Application filed December 30, 1906. Serial No. 293,924.

To all whom it may concern:

Be it known that I, RALPH C. SEYMOUR, a citizen of the United States, and resident of the borough of Manhattan, in the city and State of New York, have invented a new and useful Improvement in Cutting and Feeding Mechanism for Printing-Presses, of which the following is a specification.

My invention consists in improvements in cutting and feeding mechanism for printing presses and has for its object to provide certain improvements in the construction, form and arrangement of the several parts in which (1) one of a pair of rotary cutters is of novel form whereby sheets of varying lengths may be fed through the cutters from an advancing web to the printing mechanism while the cutters are being driven at a predetermined speed; (2) I provide a cutter carrier arranged to engage the advance edge of the web as the preceding sheet is cut therefrom and feed the web to the printing mechanism; (3) I arrange the axis of the cutter either oblique to or at right angles to the line of travel of the advancing web and the axis of the web carrier at right angles to the line of travel of the advancing web, the web carrier being either mounted eccentric to or concentric with the axis of the said cutter; (4) I preferably arrange the web carrier on an axis eccentric to the axis of the cutter whereby the web carrier may be brought into closer proximity to the impression cylinder of the printing mechanism at the time of feeding the advancing edge of the web thereto than the cutter blade, and (5) I drive the web carrier from the rotary cutter by a mechanism so arranged that the speed of the web carrier will be varied with respect to the speed of the cutter during one revolution thereof for permitting the web carrier to be driven at the same surface speed as the cutter at the time of cut and at a greater speed than the impression cylinder at the time the web carrier is feeding the advance edge of the web thereto.

In the accompanying drawings, Figure 1 is a partial front view of one of a pair of rotary cutters which is arranged out of parallelism with the advancing web, the web carrier shown in connection therewith being shown in parallelism with the advancing web and eccentric to the axis of the said cutter, Fig. 2 is a top plan view of the same, Fig. 3 is a detail longitudinal section through a stationary support and its adjacent parts at

one end of the cutter and web carriers, Fig. 4 is a similar view through the stationary support and its adjacent parts at the other end of the cutter and web carriers, a portion of the gearing for driving the rotary cutter being shown therein, Fig. 5 is a transverse section taken in the plane of the line A—A of Fig. 1, this view also illustrating a portion of the other cutter of the pair of cutters, the parts being in the position which they assume as the sheet is being cut from the web, Fig. 6 is a partial transverse section taken in the plane of the line B—B of Fig. 1, Fig. 7 is a section taken in the plane of the line A—A of Fig. 1, showing the parts in the position which they assume when the cutter has been rotated a half revolution, Fig. 8 is a similar section showing a portion of the first impression cylinder of a printing mechanism, the parts being in the position which they assume when the web carrier is feeding the advance edge of the web to the grippers on the first impression cylinder, Fig. 9 is a partial front view of a rotary cutter which is arranged in parallelism with the advancing web, the web carrier shown in connection therewith being also arranged in parallelism with the advancing web and mounted eccentric to the axis of the said cutter, Fig. 10 is a top plan view of the same, Fig. 11 is a transverse section taken in the plane of the line C—C of Fig. 9, this view also illustrating the cylinder which carries the cutting block which coacts with the rotary cutter blade, the parts being in the position which they assume as the sheet is being cut from the web, and Fig. 12 is a similar section in which the cutter is arranged in parallelism with the advancing web and the web carrier shown in connection therewith is also arranged in parallelism with the advancing web and mounted concentric with the axis of the said cutter.

The first impression cylinder of the printing mechanism is denoted by 1 and it is shown as being provided with a set of grippers 2 which may be opened at the required time to receive the advance edge of the web 3 by any desired means, as for instance, a stationary cam, shown in dotted lines at 4, in Fig. 8, arranged to operate on a roller 5 carried by an arm 6 fixed to the gripper shaft 7. The grippers are held normally closed by a spring-actuated arm 8 also fixed to the shaft 7. The blades 24, 25, of the pair

of rotary cutters are arranged to co-act with each other every complete revolution of the cutters and are driven at the same surface speed as the impression cylinder 1, the carrier 26 for the blade 25 having gears 27, 28 which mesh with gears 31 fixed to the shaft 29 of the carrier 30 for the blade 24; one of which gears 31 is shown herein, viz: the one which meshes with the gear 27. The gear 28 is driven from a gear 32 fixed to rotate with the first impression cylinder 1 and connected by any suitable driving mechanism, not shown herein.

The axes of the cutters in the form shown 15 in Figs. 1 to 8 inclusive, are arranged oblique to the line of travel of the web 3 and the cutter blades 24, 25, are arranged out of parallelism with the axes of their carriers and in lines which are spiral or oblique relatively to a line parallel with such axes so as to produce the required shearing cut on the web whereby the cut will be made at right angles to the web. This arrangement is the well known Cottrell type of cutter 25 such as is shown, described and claimed in United States Letters Patent No. 391,949, dated October 30 1888 entitled paper cutting machine, and granted to Calvert B. Cottrell.

30 To permit shorter length of sheets to be passed through the cutting mechanism than has heretofore been possible, I make the cutter carrier for the blade 25 of crank form, its shaft sections 34, 35, being in alinement 35 and its offset portion 36 at the ends of the crank arms 37, 38, forming a support for the said cutter blade 25. The shaft sections 34, 35, are mounted to rotate in stationary supports 39, 40, carried by the framing 26 40 of the machine. The gear 27 is shown as fixed to the shaft section 34 and the gear 28 as fixed to the shaft section 35 of the cutter carrier, exterior to the framing 26.

The web carrier is shown herein as a pin 45 carrier and has its axis arranged at an angle to the axis of the cutter carrier but at right angles to the line of travel of the web, the said carrier comprising two arms 41, 42, mounted on the stationary supports 39, 40 50 eccentric to the axis of the cutter carrier, the said arms being connected by an offset portion 43 located adjacent to and back of the cutter blade 25.

The web carrier is driven from the cutter 55 carrier in the present instance by providing the crank arms 37, 38 of the cutter carrier with rearwardly extended branches 44, 45, having elongated slots 46 and providing the arms 41, 42 of the web carrier with rearwardly extended branches 47, 48, in which stud shafts 49, 50 are mounted to rotate, the said stud shafts being provided with eccentric cams 51 located in the elongated slots 46 of the branches 44, 45, of the cutter 60 carrier.

The stationary supports 39, 40 have fixed thereto gears 52, 53, concentric with the axis of the web carrier and eccentric to the axis of the cutter carrier, around which gears are fitted to travel in mesh therewith, gears 54, 70 75, fixed to the stud shafts 49, 50, carried by the web carrier. These parts are so related that as the cutters are rotated at the same speed as the surface speed of the impression cylinder, the movement of the web carrier will be retarded during the first half of the revolution of the cutters after the preceding sheet has been severed from the web and will be accelerated during the second half of the revolution. This web carrier because of its 80 being mounted eccentrically to the axis of rotation of the cutter carrier, will describe a circular path which will be beyond the path of the cutter when passing the set of grippers on the impression cylinder. It is also desirable that the path of the web carrier shall be at or within the path of the cutter at the point where the two cutters co-act to sever the sheet from the web. 85

The type of web carrier shown herein is a 90 pin carrier and the pins are denoted by 56 and they are mounted to slide in the offset portion 43 of the pin carrier. The movements of these pins are controlled by a rock-shaft 57 which is provided with an arm 58 connected to spring actuated means 59 tending to slide the pins outwardly into engagement with the advance edge of the web at the time the preceding sheet is cut therefrom, and an arm 60 carrying a roller 61 arranged 95 to be engaged by a stationary cam 62 fixed in the present instance to the stationary support 40 of the framing 26. This cam 62 is so arranged that the pins 56 will be held in their withdrawn position until the sheet is about 100 to be severed from the web when the pins will be released and permitted to engage the 105 advance edge of the web.

In operation, it is to be understood that the rotary cutters are being driven at the 110 same surface speed as the printing mechanism, an impression cylinder of which is shown herein, and that the web 3 is to be driven at the same speed as the cutters at the time of cut, the means for driving the web not being shown herein as it forms part of a co-pending application filed by me of even date herewith Serial No. 293,923. The driving connection between one of the cutters and the web carrier is such that as the sheet is being severed 115 from the web, the web carrier is being driven at the same speed as the cutter. As the cutter is rotated the first half of its revolution, the speed of the web carrier is gradually retarded owing to the eccentric cam connection between the cutter and web carriers. The speed of the web carrier is then accelerated beyond the surface speed of the cutter 120 during the second half of its revolution so that the advance edge of the web is fed into 125 130

the grippers on the impression cylinder at a greater speed than the surface speed of the cylinder thereby insuring the positive engagement of the advance edge of the web by 5 the said grippers. Furthermore, because of the eccentricity of the axes of the cutter and web carriers, the web carrier is brought into closer proximity to the grippers on the impression cylinder than the cutter blade at the 10 time that the advance edge of the web is fed into the grippers.

In the form shown in Figs. 9 to 12 inclusive, the axis of the cutter is arranged at right angles to the line of travel of the web 15 instead of obliquely thereto as in the form shown in Figs. 1 to 8 inclusive, and the cutter is herein provided with a serrated blade 25* which is arranged parallel to the axis of the cutter. In the form shown in Figs. 9, 20 10 and 11, the web carrier is mounted eccentric to the axis of the cutter so as to bring the web carrier beyond the path of the cutter blade as the web is being fed to the first impression cylinder. In the form shown in Fig. 25 12, the web carrier is shown as mounted concentric with the axis of the cutter. In all of these forms the driving connection between the cutter carrier and the web carrier is such as to retard and accelerate the speed of the 30 web carrier with respect to the constant rotary speed of the cutter.

By making the cutter carrier of crank form it will be seen that short sheets may be fed through the cutters to the printing mechanism without varying the speed of the cutters.

What I claim is:

1. A rotary cutter and a web carrier driven thereby and located at the back of the cutter blade, the axis of rotation of the cutter being 40 at an angle to the axis of rotation of the web carrier.

2. A rotary cutter and a rotary web carrier driven thereby and located at the back of the cutter blade, the axis of the rotary cutter being oblique to the line of travel of the advancing web and the axis of the web carrier being arranged at right angles to the line of travel of the advancing web.

3. A rotary cutter, a web carrier arranged 50 to rotate therewith, said web carrier being located at the back of the cutter blade, and means for retarding and advancing the web carrier.

4. A rotary cutter and a rotary web carrier driven thereby located at the back of the cutter blade, the driving connection between the cutter and web carrier being such that the movement of the web carrier is retarded and accelerated during one revolution of the 60 cutter.

5. A rotary cutter and a rotary web carrier mounted eccentrically to the axis of the cutter whereby the circular path of the web carrier extends beyond the circular path of the cutter 65 during part of the revolution of the cutter.

6. A rotary cutter arranged to travel at a predetermined speed and a rotary web carrier arranged to travel at varying speeds.

7. A rotary cutter arranged to travel at a predetermined speed and a rotary web carrier 70 arranged to travel at a speed greater than the cutter during one part of the movement of the web carrier.

8. A rotary cutter arranged to travel at a predetermined speed, a rotary web carrier 75 mounted eccentrically to the axis of the cutter whereby the circular path of the web carrier extends beyond the circular path of the cutter during part of the revolution of the cutter, the said web carrier being arranged to travel at a greater speed than the cutter during part of the revolution of the web carrier.

9. The combination with an impression cylinder of a printing mechanism, of a rotary cutter driven at the same surface speed as the 85 impression cylinder, grippers on the impression cylinder and a rotary web carrier mounted eccentrically to the axis of the rotary cutter whereby the circular path of the web carrier extends beyond the circular path of the cutter 90 at a point adjacent to the impression cylinder.

10. The combination with an impression cylinder of a printing mechanism, of a rotary cutter driven at the same surface speed as the impression cylinder, grippers on the impression cylinder, and a rotary web carrier arranged to travel at a greater speed than the speed of the impression cylinder when the carrier is in proximity to the grippers.

11. The combination with an impression cylinder of a printing mechanism, of a rotary cutter driven at the same surface speed as the impression cylinder, grippers on the impression cylinder and a rotary web carrier mounted eccentrically to the axis of the cutter 105 whereby the web carrier is brought into closer proximity to the impression cylinder than the cutter, the said rotary web carrier being arranged to travel at a greater surface speed than the impression cylinder when the 110 carrier is in proximity to the grippers on the impression cylinder.

12. A rotary cutter and a rotary web carrier arranged to travel at the same speed as the cutter at the moment of cut and at a 115 greater speed than the speed of the cutter at another point in the revolution of the web carrier and cutter.

13. A rotary cutter arranged to travel at a predetermined speed, a rotary web carrier 120 and means for gradually retarding the speed of the web carrier during one part of its revolution and gradually accelerating its speed during another part of its revolution, the surface speeds of the cutter and web carrier being the same at the moment of cut.

14. A rotary cutter, means for driving it at a predetermined speed and a rotary web carrier driven from the rotary cutter at varying speeds.

15. A pair of rotary cutters having their blades arranged to coact with each other, one of the cutters being of crank form having an offset portion forming a support for its cutter blade. 35
16. A pair of rotary cutters having their blades arranged to coact with each other, one of the cutters comprising two shaft sections spaced apart and in alinement with each other, two crank arms and an offset portion forming a support for the cutter blade. 40
17. A rotary cutter carrier mounted in a stationary support and a rotary web carrier mounted on a stationary support, the said 45
- 15 web carrier having a geared connection with the stationary support and a cam connection with the cutter carrier whereby the speed of the web carrier is varied with respect to the speed of the cutter carrier.
- 20 18. A rotary cutter carrier mounted in a stationary support and a rotary web carrier mounted on the stationary support, the said web carrier having a geared connection with the stationary support and an eccentric cam 50
- 25 connection with the cutter carrier whereby the speed of the web carrier is varied with respect to the speed of the cutter carrier. 55
19. A rotary cutter carrier mounted in a stationary support and a rotary web carrier 60
- 30 mounted on the stationary support eccentrically to the axis of the cutter carrier, the said web carrier having a geared connection with the support and a cam connection with the
- cutter carrier whereby the speed of the web carrier is varied with respect to the speed of the cutter carrier and their rotary paths are different. 65
20. A rotary cutter carrier mounted in a stationary support and a rotary web carrier mounted on the stationary support eccentrically to the axis of the cutter carrier, the said web carrier having a geared connection with the stationary support and an eccentric cam connection with the cutter carrier whereby the speed of the web carrier is varied with respect to the speed of the cutter carrier and their rotary paths are different. 70
21. A rotary cutter carrier of crank form having its shaft sections mounted in a stationary support and a rotary web carrier mounted on the stationary support, the said web carrier having a geared connection with the stationary support and an eccentric cam connection with the cutter carrier whereby the movement of the web carrier is varied with respect to the movement of the cutter carrier. 75

In testimony, that I claim the foregoing as my invention, I have signed my name in presence of two witnesses, this 28th day of December 1905.

RALPH C. SEYMOUR.
